UNITED STATES PATENT OFFICE

136,481

DESIGN FOR A RING

Russell S. Bartmess, Chicago, Ill., assignor to Montgomery Ward & Co., Chicago, Ill., a corporation of Illinois

Application December 26, 1942, Serial No. 109,145

Term of patent 14 years

To all whom it may concern:

Be it known that I, Russell S. Bartmess, a citizen of the United States, residing at Chicago, in the county of Cook and State of Illinois, have invented a new, original, and ornamental Design for a Ring, of which the following is a specification, reference being had to the accompanying drawing, forming a part thereof.

The characteristic features of my design reside in the portions shown in solid lines.

What is claimed is:

The ornamental design for a ring, substantially as shown and described.

RUSSELL S. BARTMESS.
